UNITED STATES PATENT OFFICE

2,089,002

CONTROL MECHANISM FOR GRINDING MACHINES

Peter Plantinga, Amherst, Mass., assignor to
Greenfield Tap & Die Corporation, Green-
field, Mass., a corporation of Massachusetts

Application May 20, 1935, Serial No. 22,303

5 Claims. (Cl. 51—165)

This invention relates to control mechanism for a grinding machine and relates more particularly to improvements in the control mechanism shown in my prior Patent No. 1,873,151, issued August 23, 1932.

In said prior patent I disclosed means for controlling the cross feed of a grinding machine during the grinding operation and for gradually decreasing the rate of feed. I also provided means to stop the feed and to withdraw the wheel for a wheel-truing operation before the finish grinding, together with means for automatically effecting the finish grinding and for stopping the feed a second time at the end of the finish grinding operation.

It is sometimes found desirable to stop the cross feed before actual completion of the total grinding cycle and more particularly at the end of the rough grinding operation, and in such a way that it will not require the attention of the operator.

It is the general object of my invention to provide auxiliary means for thus automatically stopping the feed at any selected point before or at the completion of the rough grinding operation and without changing the setting of the automatic control mechanism.

I also provide a construction by which said automatic disabling means may be rendered inoperative when desired.

My invention further relates to arrangements and combinations of parts which will be herein-after described and more particularly pointed out in the appended claims.

A preferred form of the invention is shown in the drawings, in which

Fig. 1 is a partial front elevation of the cross feeding mechanism of a grinding machine;

Fig. 2 is a sectional side elevation, taken along the line 2—2 in Fig. 1;

Fig. 3 is a detail side elevation, looking in the direction of the arrow 3 in Fig. 1;

Fig. 4 is a plan view, looking in the direction of the arrow 4 in Fig. 1;

Fig. 5 is a front elevation of certain parts, as indicated by the line 5—5 in Fig. 4;

Fig. 6 is an enlarged front elevation of certain parts shown in Fig. 1, and

Fig. 7 is a sectional side elevation, taken along the line 7—7 in Fig. 4.

My improvements are particularly adapted for use on a grinding machine of the type in which the grinding wheel is mounted for transverse or cross feeding adjustment radially of the work, and in which the work is mounted for reciprocating

axial movement relative to the grinding wheel.

I will first describe briefly the mechanism shown in my prior patent for feeding the grinding wheel transversely toward or from the revolving work. Referring particularly to Figs. 1 and 2, a cross feed shaft 30 is mounted at its outer end in a fixed bearing 31 and is provided with a disc 32 fixed to said shaft and having a ratchet wheel 33 and ring gear 34 mounted thereon. The shaft 30 is effective to move the wheel slide through any usual operating connections or gearing not shown.

An outer flange 35 of the disc 32 also forms a gear engaged by a pinion 36 mounted in a hand wheel 37 and normally held from relative rotation therein. The pinion 36 may be turned manually in its bearing in the hand wheel when relative adjustment of the hand wheel and disc 32 is desired. A cam ring 40 is mounted on the disc 32 and is moved angularly therewith.

A feed pawl 41 (Figs. 1 and 2) is fixed to a stud 43 pivoted in a pawl carrier 44 slidable on parallel rods 45. A second pawl 42 is loose on the stud 43. A spring 46 (Fig. 1) is connected to a stud 47 (Fig. 4) fixed in the pawl 41 and projecting loosely into an enlarged opening in the pawl 42. The spring 46 has a rearwardly projecting end 48 engaging the back edge of the pawl 42.

The pawls are so arranged that the point of one pawl is a half-tooth to the rear of the point of the other pawl, so that a half tooth feed can be taken if desired. The carrier 44 is forced rearward or to the right in Figs. 1 and 4 by a coil spring 50 (Fig. 4).

An upwardly projecting arm 52 (Figs. 1 and 4) is formed as part of a bell crank 53 mounted on a pivot stud 54. The arm 52 engages the rear end of the pawl carrier 44 and the laterally projecting arm of the bell crank 53 is provided with a cam roll 55 engaging the cam ring 40 previously described. The cam is provided with steps or concentric portions at different distances from its axis, as clearly shown in Fig. 1, and the greater the radius of the cam step, the smaller return or non-feeding movement of the pawl carrier 44 will take place.

The limit of advance movement of the carrier is fixed and consequently the rate of cross feed is determined by the steps on the cam 40. Each cross feeding movement at the beginning of the grinding operation is fairly large, but the extent of movement is progressively decreased as the grinding approaches finish size.

- The mechanism for giving the pawl carriage or carrier 44 its feeding movement comprises a rocker 57 (Fig. 5) loosely mounted on the pivot stud 54 previously described and provided with an adjustable contact screw 60 adapted to engage the rear face of the upwardly extending arm 52 of the bell crank 53. A portion 61 of the rocker 57 is positioned above a stud 62 adjustably secured in the upper end of a piston rod 63 connected to an actuating piston in a hydraulic cylinder 65. Pressure is admitted below said piston at the limit of work travel, and at each feeding operation the piston moves the rod upward until the piston engages a fixed stop.
- During the normal operation of the machine, the feed pawls are thus actuated hydraulically by mechanism controlled by the work table, but the extent of each feeding movement is controlled by the cam ring 40.
- When the cross feed is to be automatically reversed to withdraw the wheel from the work, it is necessary to first disengage the feed pawls. For this purpose I provide a release lever 150 (Figs. 1 and 4) fixed to the stud 43 to which the feed pawl 41 is also secured and on which the feed pawl 42 is loosely mounted.
- The outer end of the lever 150 is provided with an extended surface 151 (Fig. 4) underlying an arm 152 fixed to the end of a rod 153 slidably mounted in a fixed bearing 154 (Fig. 1). An arm 155 is fixed to the opposite end of the rod 153 and is provided with a cam roll 156 positioned to engage a cam 157. The cam 157 is formed with three equally spaced raised portions 157a, one of which is indicated in Fig. 3.
- When the cam roll 156 engages one of the depressed portions of the cam 157, the arm 152 is raised by a spring 164 (Fig. 1) and the feed pawls 41 and 42 are free to engage the ratchet wheel 33.
- When the roll 156 is raised by one of the high parts 157a of the cam 157, the arm 152 is depressed and the feed pawls are raised out of engagement with the ratchet wheel 33.
- As previously stated, it is desirable on occasion to discontinue the cross feed, independently of the action of the regular control mechanism. For this purpose I have provided the release lever 150 with an arm 160 (Figs. 4 and 6) having a cam portion 161 formed at the outer end thereof.
- I also provide a spring plunger 162 (Fig. 7) mounted in a recessed portion 163 of a plate 164 which may be secured to the face of the cam 40 by clamping screws 165.
- The cam 40 is preferably provided with segmental recesses 166 and segmental slots 167 permitting limited circumferential adjustment of the plate 164. An adjusting screw 170 loosely rotatable in a projection 171 on the cam 40 is threaded into a swiveled member 172 mounted in the plate 164 and constitutes means for closely adjusting the plate 164 and plunger 162 to a desired position.
- The plunger 162 is forced outward by a spring 173 and its outward position is determined by a stop pin 175, normally seated in the end of slots 176 (Fig. 4) in a hub portion 177 through which the plunger slides. A knob 178 is provided for drawing the plunger 162 forward when desired.
- If it is desired to stop the cross feed of the grinding machine before the regular control cam 157 acts, the plate 164 is secured on the cam 40 in such a position that the plunger 162 will engage the cam-shaped end 161 of the arm 160 and will move the arm 160 upward, thereby lifting the

feed pawls 41 and 42 out of engagement with the ratchet wheel 33.

When it is thereafter desired to again start the automatic feed, the operator merely withdraws the plunger 162 by grasping the knob 178 and pulling the same forward. This allows the arm 160 to drop and release the feed pawls, whereupon automatic feeding is resumed.

If it is desired to render the auxiliary stopping device inoperative, the operator pulls the plunger forward by the knob 178 until the stop pin 175 is out of the slots 176, after which he turns the knob and plunger 90° and seats the stop pin in the shallow notches 180 (Fig. 7). When the parts are in this position, the plunger 162 is withdrawn to inoperative position with respect to the arm 160.

With this device, the cross feed may be stopped at any desired point prior to the completion of a grinding operation as determined by the regular control mechanism, and the exact point at which the cross feed is stopped can be determined and adjusted by the circumferential setting of the plate 164.

This auxiliary device is found to be of great utility when it is for any reason desirable to operate the grinding machine semi-automatically and to provide for the interruption of a grinding operation without the personal supervision of the operator.

It will be particularly noted that the setting of the regular control device remains unchanged and that said device is in full and regular control whenever the auxiliary device is rendered inoperative.

Having thus described my invention and the advantages thereof, I do not wish to be limited to the details herein disclosed, otherwise than as set forth in the claims, but what I claim is:

1. In a grinding machine having a grinding wheel and a cross feed mechanism therefor, in combination, means to stop the cross feed after a predetermined grinding period, and auxiliary means to interrupt said cross feed at a selected and earlier time in said grinding operation, said auxiliary means comprising a release member, a device to engage and actuate said member, and means to free said member from said device after the cross feed is stopped thereby.

2. In a grinding machine having a grinding wheel and a cross feed mechanism therefor, in combination, means to stop the cross feed after a predetermined grinding period, and auxiliary means to interrupt said cross feed at a selected and earlier time in said grinding operation, said auxiliary means comprising a release member, a device rotating adjacent thereto, a spring plunger mounted on said rotating device, and selective means to hold said plunger in operative or inoperative position with respect to said release member.

3. In a grinding machine having a grinding wheel and a cross feed mechanism therefor, in combination, means to stop the cross feed after a predetermined grinding period, auxiliary automatic means to render said cross feed inoperative at an earlier predetermined point in the grinding operation, the set-up of the cross feed mechanism and of the stopping means remaining unchanged, and manual means to render said cross feed mechanism again operative at the identical point in the cross feed operation at which the cross feed was automatically interrupted.

4. In a grinding machine having a grinding

wheel and a cross feed mechanism therefor, in combination, actuating devices for said cross feed mechanism, means to stop the cross feed after a predetermined grinding period, means to disengage said actuating devices at an earlier predetermined point in the grinding operation, and manual means to effect reengagement of said actuating devices at the identical point in the cross feed operation at which the cross feed was interrupted.

5. In a grinding machine having a grinding

wheel and a cross feed mechanism therefor, in combination, actuating devices for said cross feed mechanism, means to stop the cross feed after a predetermined grinding period, means to disengage said actuating devices at an earlier 5 predetermined point in the grinding operation, and manually operable means to withdraw and hold said disengaging means in inoperative position to permit continued operation of said cross feed mechanism.

10
